[57] CLAIM

The ornamental design for an all terrain wheel for a wheelchair, as shown and described.

DESCRIPTION

FIG. 1 is a front elevational view of an all terrain wheel for a wheelchair showing my new design, wherein a tire fitted to the all terrain wheel is indicated in broken lines; FIG. 2 is a top plan view of the all terrain wheel of FIG. 1, with the tire shown in broken lines, the bottom plan view, left end elevational view and right end elevational view being identical thereto;

FIG. 3 is a rear elevational view thereof; and,

FIG. 4 is a sectional view taken along the plane indicated by the line 4—4 of FIG. 3.

The broken line showing of environment is illustrative purposes only and forms no part of the claimed design.
